TOOTH CLEANSER

Filed May 19, 1936

FIG. 2.

INVENTOR:
KATE M. REMINGTON

BY
S. A. Neuch
ATTORNEY.

UNITED STATES PATENT OFFICE

2,092,987

TOOTH CLEANSER

Kate M. Remington, Santa Cruz, Calif.

Application May 19, 1936, Serial No. 80,547

3 Claims. (Cl. 15—227)

My invention relates to tooth cleaning devices and more particularly to such devices as are adapt to be supported on and manipulated by the finger.

5 A few of the objects of my invention are to provide a "finger stall" type of tooth cleansing device which has a highly efficient scrubbing action on the teeth; one which is easy to use and keep clean; one which has a long useful life; and one 10 which is relatively inexpensive to manufacture.

The manner of accomplishing the foregoing objects as well as further objects and advantages will be understood from the following description taken together with the accompanying drawing,

15 in which:

Fig. 1 is a perspective view of a preferred form of my invention.

Fig. 2 is a cross sectional view taken on the line 2—2 of Fig. 1.

20 Fig. 3 is a perspective view showing the finger hole of my invention opened to permit insertion of a finger thereinto.

Fig. 4 is a perspective view of the device of my invention mounted on a finger in readiness for 25 use.

Referring specifically to the drawing, the preferred form of my invention is seen to comprise a cleaner 10 comprising a woven or knitted tube 11 having an end 12 thereof closed tightly and an 30 end 13 thereof open. This tube 11 is preferably provided exteriorly with terry cloth pile 14.

35 Preferably about midway between ends 12 and 13, the tube 11 has a hole 15 therein made with a button hole machine to prevent unravelling of the material adjacent thereto. That portion of the tube 11 between the hole 15 and open tube end 13 comprises the handle 16 of the cleaner.

In order to use this device the handle 16 is 40 seized as shown in Fig. 3 causing the finger hole 15 to gape somewhat. The forefinger of the

other hand is now inserted into the hole 15 until the end 12 of the device fits snugly over the tip of the finger as shown in Fig. 4. The handle 16 is now grasped between this same forefinger and the thumb of the same hand thereby retaining 5 the cleaner 10 on the finger while it is being used.

The cleaner 10 may be impregnated with cleansing material or some other material which it is desired to apply, or it may be free from any 10 such material depending upon the particular use to be made of the invention.

What I claim is:

1. As an article of manufacture, a cleaning device, comprising: a tube formed of knitted material with a heavy pile formed on the outer surface thereof, said tube being closed at one end and having an aperture provided therein substantially midway between the ends thereof for the insertion of the finger into the closed end thereof to 20 provide a finger stall, the remaining length of said tube serving as a handle. 15

2. As an article of manufacture, a cleaning device, comprising a tube formed of fabric and having one end thereof closed, there being an opening provided therein in between the end portions thereof for the insertion of the finger into the aforesaid closed end thereof to provide a finger stall, the remaining length of said tube serving 25 as a handle. 30

3. As an article of manufacture, a cleaning device, comprising a tube formed of fabric and having one end thereof closed, there being a button hole opening provided therein in between the end portions thereof for the insertion of the finger 35 into the aforesaid closed end thereof to provide a finger stall, the remaining length of said tube serving as a handle.

KATE M. REMINGTON. 40
